[57] ABSTRACT

A pad gripping device for a hand-held appliance, such as an electric dry shaver, comprising an envelope containing a cushion member and frame member wherein fastening means extend from the frame member outwardly of the envelope for locking engagement with wall portion of the appliance casing and which fasteners in locking position flex the pad to conform to the outer surface of the casing.

4 Claims, 8 Drawing Figures

PAD GRIPPING DEVICE

BACKGROUND OF THE INVENTION

This invention relates to new and useful improvements in pad gripping devices for hand-held appliances.

In hand-held electrical appliances such as electric dry shavers the use of pad gripping devices has become increasingly more desirable. These pads, certain of which are of the general type shown in U.S. Pat. Nos. 3,171,567 and 3,341,887, usually comprise an envelope containing a soft pillow-like inner cushion disposed on a backing member. The pads are arranged on the opposite faces of the appliance and the user grips the appliance in the cup of his hand with his fingers imbedded in the pads.

Pad gripping devices not only increase the esthetic appearance of the appliance but more importantly allow the user to grip the casing in a comfortable manner reducing the risk of the casing slipping from his grasp during use. This is quite pertinent in appliances such as an electric shaver where the appliance is continually moved back and forth across the user's face and where slight vibrations from the motor within the casing are transmitted through the walls thereof to the fingers of the user.

In prior art devices such as those disclosed in the aforementioned patents it has been the usual practice to secure these pad devices by adhesives to the casing wall or alternatively provide metal tabs on the pad device which are adapted to be inserted into openings in the walls of the casing and then bent over in securing relationship against the inner wall surfaces thereof. Although these known pad devices have met with considerable success, various difficulties have been encountered in use and assembly of the pads to the shaver appliance casing. In instances where the pads are secured by metal tabs additional insulating means are required to cover the tabs as a precautionary measure against possible electrical shocks. In other devices where adhesives are used to secure the pad to the casing the contour of the casing which usually range from flat to slightly convex do not at all times permit proper binding of the pad device to the outer casing walls.

It is the object of the present invention to provide novel pad gripping means for a hand-held appliance.

Another object is to provide a novel pad gripping device which readily conforms to the surface configuration of the wall of the appliance casing.

Another object is to provide novel means for mounting a pad gripping device to an appliance casing which also includes self-insulating means.

A still further object is to provide a novel pad gripping device which is readily adaptable to rapid manufacturing and assembly procedures resulting in a cost saving both in labor and parts.

SUMMARY OF THE INVENTION

This invention contemplates a novel pad gripping device for a hand-held appliance such as an electric dry shaver. The pad includes a pillow-like inner cushion member disposed within an envelope comprising on a backing member and a cover member of soft material provided over the cushion and which members have marginal edge portions secured to each other to form the envelope. Means are provided within the assembled pad for conforming the pad to the surface of the casing wall and for mounting the pad thereon. These means

2 include a flexible metal frame insert member interposed between the cushion and the backing member. Fastener means are provided on the insert member operable to interlock the pad envelope to the casing walls and flex the insert member to allow the assembled pad to conform closely to the contour of the outer surface of the casing wall upon which it is mounted.

The above and other objects and advantages of the present invention will appear more fully hereinafter from a consideration of the detailed description which follows taken together with the accompanying drawings wherein one embodiment of the invention is illustrated.

DESCRIPTION OF THE DRAWING

In the drawings:

FIG. 1 is a front perspective view of the electric dry shaver casing and to which casing is attached an embodiment of a pad device constructed according to the present invention;

FIG. 2 is a side elevational view of the electric dry shaver of FIG. 1 with portions of the casing and the pad device broken away to show the interior structure of the pad device;

FIG. 3 is a side elevational view showing the parts of the pad device in exploded relationship;

FIG. 4 is a front view of the pad device with parts thereof broken away to show portions of the interior;

FIG. 5 is a sectional view taken on the line 5—5 of FIG. 2;

FIG. 6 is an enlarged fragmentary view of the pad mounting fasteners;

FIG. 7 is a sectional view taken on the line 7—7 of FIG. 6; and

FIG. 8 is a sectional view taken on the line 8—8 of FIG. 6.

DETAILED DESCRIPTION

Referring now to the drawing for a more detailed description of the present invention and more particularly to FIGS. 1 and 2, wherein one preferred embodiment of the invention is shown, a pad gripping device is generally indicated by the reference numeral 10. Pad devices 10 are mounted on opposite faces of an electric dry shaver casing 12 and which shaver is generally indicated by the reference numeral 14.

Casing 12 is formed of a hard smooth plastic material as for example nylon, and houses therein a motor (not shown) and means operative thereby for effecting operation of a cutter head assembly 16 in a well-known manner. Casing 12 includes a lower container portion 17 and an upper section 18 commonly referred to as a hair pocket which is removably mounted over the cutter head assembly 16. The opposite faces of casing 12 are provided with framed recess portions 20 in which are disposed pad devices 10. In use the shaver 14 is held in the cupped hand of the user with the tips of the user's fingers embedded in pads 10 providing a comfortable gripping area. As shown in FIGS. 1 and 2 and 3 the surface of the shaver casing is of a generally smooth configuration and pads 10 further aid in preventing accidental slippage of the casing from the user's grip.

Each pad device 10 includes a generally rectangular shaped base or backing member 22 and an inner cushion member 24 comprised of a thick layer of resilient material such as a vinyl foam substance is mounted on backing or base member 22. A facing or cover member

26 of soft material such as flexible vinyl plastic is disposed over cushion 24 and has peripheral edge portions FIG. 4 secured to the peripheral edges of base member 22.

As mentioned it is a feature of this invention to provide novel means for mounting pads 10 on casing 12 in conformity with the outer surface and in secured relationship thereto. To this end a rectangular metal insert plate 28 which is slightly convex in shape and of slightly less perimetrical dimension than backing member 22 is disposed in pad 10 interposed between cushion 24 and base 22.

Fastening means for mounting pads 10 on casing 12 include a pair of plastic insulating locking members 30 carried by insert 28 for insertion in spaced apertures 31 in the walls of casing 12. Each fastener 30 (FIGS. 7 & 8) comprises a circular base 33, a hub portion 34 and a head portion 35. Locking tabs 36 on head portion 35 project through aligned apertures 38 and 40 respectively provided in base 22 and insert 28. Spaced locking fingers 42 are formed on insert 28 adjacent each aperture 40 for engagement in spaced recesses 44 (FIG. 7) on base 22 of fastener 30 in manner to be hereinafter explained. In addition spaced openings 46 are provided in insert 28 and corresponding openings 47 in base 22 for releasing air from pad 10 when pressure is applied to cover 26 by the fingers of the user.

Prior to mounting a pad device 10 on casing 12 fasteners 30 are rotated 90° from the position shown in FIG. 6 whereby tabs 36 on head 35 of each fastener 30 are aligned as shown in FIG. 4 with corresponding apertures 31 (FIG. 1) in the face wall of casing 12. In this position fasteners 30 may be readily inserted into openings 31. In this position the base 33 overlies the locking finger 42 on insert 28. Once fasteners 30 are inserted into casing opening 31 the fasteners may be manually rotated from within the casing by means of an instrument such as suitable pliers by grasping tabs 36 and rotating fasteners 90° to the position shown in FIGS. 1 and 6. In this position fingers 42 on insert 28 lie in recesses 44 on base 33 of fasteners 30 and tabs 36 on the head are engaged against the inner wall surfaces of lower container 17 of casing 12. Further, tabs 36 are locked to the walls of casing 12, insert 28 is flexed slightly causing pad 10 to conform closely against the outer surface of casing 12.

It is apparent from the foregoing that the novel pad member described has many advantages. The novel fasteners provides self-insulating plastic means and the locking action thereof in cooperation with flexible insert provide a pad device which conforms closely to the surface of the casing without use of adhesive sub-

stances or the like. The fastening arrangement allows for increased savings in assembly cost in reducing the number of parts and time required in manufacturing for mounting the pads to the casing.

Although one embodiment of the pad mentioned has been illustrated and described in detail, it is to be understood that the invention is not limited thereto. Various changes can be made in the design and arrangement of parts without departing from the spirit and scope of the invention as the same will now be understood by those skilled in the art.

What is claimed is:

1. A pad gripping device adapted to be mounted on the outer surface of a hand-held appliance, said gripping device comprising,
  - a pillow-like pad assembly including a backing member and a resilient cushion disposed on said backing member,
  - means for mounting said pad on the outer surface of the casing of the appliance,
  - a flexible support plate being part of said assembly,
  - fastener means associated with said plate and having portions extending outwardly of said pad assembly adapted for locking engagement with the appliance casing, said fastener means in said locked position being adapted to flex said support plate to conform said pad to the surface of the appliance, and
  - said fastener means including at least one locking member having a base portion and a shaft extending outwardly of the pad assembly and having tab portions adapted to be rotated into locking engagement with the shaver casing.
2. The pad gripping device of claim 1 wherein tabs are formed on the ends of the shaft for locking engagement with the inner wall surface of the appliance casing.
3. The pad gripping device of claim 2 wherein said fastener is formed of insulating material to insulate said pad member from said appliance.
4. The pad gripping device of claim 2 wherein said appliance is provided with a recess framing portion on the outer surface thereof to receive said pad assembly, said pad assembly being provided with a plurality of said fasteners, a plurality of openings in said casing and within said framing portion for receiving said fasteners, and said fasteners in said locked position with the inner wall surface of said casing adapted to flex said pad assembly into close contact with the surface of said casing within said framing portion.
